AUTOMATIC LIGHTER SYSTEM FOR VAPOR FUEL STOVES

George E. Pickup, Newark, Ohio, assignor, by
mesne assignments, to Florence-Wehrle Stove
Co., Newark, Ohio, a corporation of Ohio.

Application November 22, 1935, Serial No. 51,137

4. Claims. (CL. 158—85)

This invention relates to improvements in vapor fuel stoves and more particularly concerns a novel automatic lighter system for such stoves.

A principal object of the invention resides in the provision of a novel lighter system for vapor fuel stoves by which one or more vapor burners may be automatically lighted from a remotely disposed flame which burns continuously while the stove is in use, merely by admitting fuel vapor to the burner to be lighted.

Another object resides in the provision of an automatic lighter system for vapor fuel stoves in which means is appropriately arranged to convey vapor fuel into the combustion zone of a lighted burner to ignite the vapor and carry the resulting flame to the burning zone of the burner to be lighted.

Another object resides in the provision, in a fuel stove embodying a system having an auxiliary burner which remains burning while the stove is in use and a plurality of principal burners only one of which is disposed with relation to the combustion zone of the auxiliary burner to be ignited thereby, of automatic lighter means for igniting any one or more of the remaining burners from the combustion zone of the auxiliary burner as an incident to the admission of vapor fuel to the burner to be lighted.

Further objects reside in providing an improved auxiliary burner construction including means for supporting the vapor ducts of the lighter system; in providing a novel arrangement for delivering fuel vapor freely from the burner to be lighted to the lighter mechanism while preventing the entrance of flame to the interior of the burner; in the novel construction by which the lighter mechanism is supported to permit removal of any burner without disturbing the operation of the system with respect to any remaining burner; and in the improved construction and relationship of parts by which the foregoing and ancillary objects of the invention are carried into effect.

Other objects and advantages will become apparent from the following description taken in connection with the accompanying drawing, in which:

Figure 1 is a fragmentary plan view of the burner system of a vapor fuel stove embodying the principles of the present invention.

Fig. 2 is an enlarged sectional view taken substantially along the line 2—2 of Figure 1.

Fig. 3 is an enlarged fragmentary plan view, partly in section, showing details of the arrangement whereby vapor fuel is delivered from a principal burner to the lighter system.

Figs. 4 and 5 are sectional elevational views taken substantially along lines 4—4 and 5—5, respectively, of Fig. 3.

While the invention is susceptible of various modifications and alternative constructions, I have shown in the drawing and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

By way of illustration, the invention is shown as embodied in a gasoline stove having a burner system including a manifold 10 in communication with one or more principal burners 11 which are preferably removably mounted and which are controlled in the usual manner by appropriate valve mechanisms 12. Valve stems 13 extend from the valve mechanisms 12 through the front frame 14 of the stove so as to be readily accessible for rotation by manipulable handles 15 on their outer ends. Fuel in vapor form is delivered to the manifold through an air mixer 17 from a generator tube 18, the discharge end of which projects into the air mixer and the opposite end of which extends toward the front of the stove so that the usual generator control valve may be operated by a handle 19 fixed to a stem 20 passing axially through the generator tube.

Liquid fuel to be vaporized may be supplied to the generator near its outer or inlet end by a fuel delivery conduit 22, and vaporizing heat may be furnished by an elongated auxiliary burner 23 which communicates with the manifold 10 and longitudinally underlies the generator, several burner grids 24 being provided in the flame face of the auxiliary burner for concentrating the effect of the vaporizing flame on the generator tube. For the sake of safety, a thermostatically controlled valve mechanism 25 may be interposed in the liquid fuel conduit 22, the valve mechanism being supported substantially to one side of the generator and auxiliary burner beyond their heat zone by a bracket 26. A thermally responsive rod 27 for operating the safety valve may extend between the generator tube and the auxiliary burner so as to be heated by the flame from one of the grids, the end of the rod opposite the valve being fixedly supported by a bracket arm 28.

In order to place the stove in condition for operation, the auxiliary burner 23 is lighted in the usual manner by applying a burning match or the like, and this burner remains continuously

lighted while the burner system remains in operation. Customarily one of the principal burners 11 may comprise two semicircular segments 29 and 30, one disposed on each side of the generator tube 18 and in close proximity to the combustion zone established by the auxiliary burner 23. Through this arrangement the segmental burner will ignite automatically when fuel vapor is admitted thereto because of the proximity of its 10 combustion zone to that of the auxiliary burner. Heretofore, however, no practical means has been proposed for automatically lighting the remaining one or more principal burners of a vapor fuel stove burner system.

15 The principal aim of the present invention, therefore, has been to provide a lighter system by which any burner may be automatically ignited from a continuous flame such as that supplied by the generator burner. Preferably the lighter 20 system may take the form of mechanism by which any principal burner may be ignited by the sole expedient of opening its valve 12 to admit fuel vapor from the manifold. To this end, the invention contemplates the provision of vapor conducting means, herein shown as comprising a plurality of tubes 32 providing ducts for conveying fuel vapor from any one of the remotely disposed principal burners 11 past the segmental burner to the combustion zone of the generator 25 burner, where the fuel vapor will be ignited and cause a flash-back flame extending to the combustion zone of the principal burner to light the same.

30 In the present embodiment, separate ducts 32 are shown as extending from the burners toward a common position adjacent the generator burner 23 and with their ends opening toward the combustion zone of the latter burner. Means may be provided for fixedly supporting the adjacent ends of the lighter ducts 32 as a unit. For 35 this purpose the auxiliary burner is of improved construction and may be equipped with a flange 33 forming an extension of one side of the body of the burner, and adapted to receive one leg 34 of an angle bracket 35, a bolt 37 maintaining the angle bracket firmly in position. An outstanding leg 38 on the bracket provides a shelf upon which the adjacent ends of the lighter ducts are supported. If desired, the ducts may be permanently and rigidly secured to the bracket leg 40 45 38 by brazing or a similar expedient. Through this arrangement, all of the lighter ducts are maintained permanently in position but may be quickly removed as a unit by loosening the bolt 37.

50 The fuel vapor in a stove of the present type is maintained at low pressure and when in a relatively cool condition is heavier than air. It is necessary therefore, to provide means for delivering the heavy fuel vapor from the burner 55 to be lighted to the lighter duct leading thereto. To this end, therefore, the side wall of each remote burner 11 is provided with an orifice 39 preferably near the upper wall or combustion zone of the burner. The mouth of the adjacent lighter 60 65 duct 32 is disposed in substantially coaxial, spaced relation to the orifice so that fuel vapor forced from the orifice by the slight pressure under which it is admitted to the burner will pass into the duct. The fuel vapor is then conveyed 70 through the duct to the combustion zone of the lighted burner and promptly becomes ignited throughout the length of the tube. Combustion within the lighter duct may be relatively sluggish due to the lack of air, but as soon as the 75 combustion reaches back to the mouth of the duct

where a free supply of air is available a puff or flash of flame F occurs. This flame passes upwardly toward the combustion zone of the burner, thereby causing the fuel vapor issuing from the usual burner slots 40 to become ignited.

5 A fairly critical relationship must be observed with respect to the spacing between the mouth of the lighter duct 32 and the adjacent wall of the burner 11 so that the flame F will attain proper results. The importance of this arises 10 from the necessity of an adequate supply of secondary air to produce the flame. Accordingly the proper spacing should be predetermined from a consideration of the relative proportions of the parts. In the practical embodiment illustrated 15 herein the lighter ducts are of $\frac{1}{16}$ inch exterior diameter tubing and a spacing of from $\frac{1}{16}$ inch to $\frac{3}{8}$ inch between the tube end and the mouth of the orifice 39 has been found satisfactory.

A proper axial relation of the mouth of the 20 duct 32 to the orifice 39 should also be maintained for best results. Herein this end is attained by providing a laterally projecting trough-shaped lug 41 on the wall of the burner underlying the orifice. The end of the lighter duct 25 may then rest upon the outer end of the lug in its trough-depression. As will be observed, the radius of the trough is greater than that of the duct, and space is thus provided on each side of the duct for a draft of air to the flame F. The 30 trough, moreover aids in the passage of fuel vapor from the orifice to the lighter duct, and perhaps aids somewhat in causing the flame to pass upwardly into the combustion zone of the burner.

35 The flash-back flame F occurs with a slight explosive force and in order to prevent entrance of the flame into the principal burner, suitable means is provided across the orifice 39. In the present instance, this means comprises a fitting 40 42 threadedly engaging in the orifice 39 and carrying a transverse screen 43. This screen permits free discharge of fuel vapor when igniting the burner but acts to deflect the flame and prevent its entrance to the burner, substantially as 45 indicated in Fig. 4. Once the principal burner has been lighted, practically all of the fuel vapor will pass upwardly into the combustion zone of the burner and what little may continue to pass laterally through the lighting orifice 39 will be consumed by an insignificant flame at the outside 50 face of the screen.

55 From the foregoing, it will be apparent that the present invention provides a novel lighter system by which any one or more principal burners of a vapor fuel stove may be automatically ignited by merely admitting vapor fuel to the burner. The construction and relationship of parts, moreover is of a very simple, inexpensive and efficient character.

60 I claim as my invention:

1. In combination in a lighter system for a vapor fuel stove including a burner structure embodying a manifold and means for delivering fuel vapor to said manifold, a hollow valve-controlled 65 principal burner and an auxiliary burner continuously lighted while the stove is in use both communicating with said manifold, said principal burner having an upper burner surface and being arranged for up-draft combustion, an orifice in 70 the side of said principal burner below said burner surface, said orifice being of substantial diameter to permit the discharge from said principal burner of a considerable volume of heavy fuel vapor after the burner has been turned on and before 75

any appreciable quantity has escaped through said burner surface, a lighter duct having one end in substantially spaced relation to said orifice and its other end communicating with the combustion zone of said auxiliary burner for conveying to said combustion zone fuel vapor passing from said principal burner through said orifice whereby to effect ignition of said vapor, and means for preventing entrance to the interior of the principal burner of the flame resulting as an incident to ignition of said fuel vapor.

2. In combination in an automatic lighter system for a vapor fuel stove embodying a manifold and a generator for delivering fuel vapor to said manifold, a first burner disposed relative to said generator for continuously heating the same, a hollow-body burner remotely disposed relative to said first burner, and having an upwardly disposed combustion face, an orifice in the side of said hollow-body burner below said combustion face, a vapor tube leading substantially axially from said orifice and terminating in close proximity to said first burner, and an upwardly opening trough shaped lug on said hollow-body burner below said orifice for receiving and maintaining said vapor conducting tube in operative position relative to said orifice and serving to conduct fuel vapor from said orifice into said tube and to direct upwardly toward said combustion face the flame created by ignition of fuel vapor in said tube.

3. In a fuel vapor stove embodying a generator, a generator burner, a manifold for receiving heavy low pressure fuel vapor from said generator, and a chambered principal burner communicating with said manifold and having a perforated burner top and an orifice in one side through which heavy fuel vapor initially entering said burner may flow before reaching said top; the combination of means for automatically lighting said principal burner from said generator burner including a tube having one end mounted within the

combustion zone of said generator burner and its other end spaced a predetermined short distance from the mouth of said orifice in substantial alignment therewith to receive fuel vapor flowing outwardly and downwardly therefrom, and means below said orifice and the adjacent end of said tube for conducting the heavy fuel vapor through the space between the orifice and said adjacent tube end so that the fuel vapor will travel to said combustion zone and become ignited throughout said tube, said means being constructed to permit unobstructed communication thereabove between said space and said burner top and being so related to said adjacent end of said tube that air may flow freely along the sides of said tube toward said space to insure an adequate supply of air for an explosive flash of lighting flame in said space upwardly toward said burner top as an incident to said ignition throughout said tube.

4. In combination in a vapor fuel stove of the character described, a first burner to be ignited initially in placing the stove in operation, a hollow valve-controlled second burner having a perforated burner top in a higher plane than the first burner, a lighter tube having one end within the combustion zone of the first burner and slanting upwardly toward the second burner, the side wall of the second burner having an orifice therein through which heavy fuel vapor may escape before reaching said burner top when the burner is turned on for starting, and means for supporting the upper end of said tube in predetermined spaced relation to and in alignment with the mouth of said orifice to receive fuel vapor therefrom to convey the vapor to said combustion zone for ignition to produce a flash-back flame for igniting the second burner, said predetermined spaced relation being from five-sixteenths to three-eighths of an inch where the tube is of substantially seven-sixteenths exterior diameter tubing.

GEORGE E. PICKUP.
